UNITED STATES PATENT OFFICE.

CHARLES W. DONALDSON, OF CHICAGO, ILLINOIS.

REINFORCED-CONCRETE STAIRS.

Application filed March 26, 1920. Serial No. 368,972.

To all whom it may concern:

Be it known that I, CHARLES W. DONALDSON, citizen of the United States, residing at Chicago, in the county of Cook and State 5 of Illinois, have invented certain new and useful Improvements in Reinforced-Concrete Stairs, of which the following is a specification.

This invention has to do with the erection 10 of reinforced concrete building units, and deals especially with the problem of constructing units of this class in the form of stairs susceptible of being built of metallic reinforcing and concrete or cement mortar 15 without necessitating the employment of forms such as are ordinarily required for the purpose under the conditions of common practice to-day.

The invention may be said to comprise 20 not only a complete reinforced concrete stairs of the type mentioned, but also includes what may be characterized as a stairs form unit constituting an article of manufacture. It is adapted to be set up as a part 25 of either concrete or wood building construction and availed of for making stairs of reinforced concrete.

In the practice of my invention I utilize, 30 preferably metal lath for forming the side stringers of the stairs and for forming the metal reinforcing shape for making the risers and treads, the former being suitably connected with the stringers as a preliminary, of course, to the final application of 35 concrete or cement mortar, allowed in due course to set in order to form the final complete structure.

Secondary to the foregoing I employ preferably ribbed metal lath as a reinforcing 40 material and reinforcing form, the ribs being employed in a special way, both for the stringers, treads and risers, to obtain a most advantageous construction.

Included in my invention is a special construction of intermediate stringer designed 45 for use for wide stairs, though susceptible of being employed as a side stringer if such might be desired.

Owing to the capacity of the metal lath 50 reinforcing used by me to be shaped into different forms, this material affords unusually advantageous facilities for erecting stairs of curved or other shapes, the material being adapted to be bent accordingly.

Where my stairs are used in concrete constructions involving walls of reinforced concrete the metal lath or reinforcing shaped to make the risers and treads may be connected to the wall construction to thus afford a unitary or monolithic wall and stairs 60 of advantageous construction, all of which will be appreciated more fully in connection with the following description, and on reference to the accompanying drawings, in which:

Figure 1 illustrates the assemblage of the metal lath forming the risers and treads, and a side stringer, in longitudinal section.

Figure 2 is a similar view, but showing 70 the application of the cement mortar or concrete to the metallic reinforcing as in the completed construction.

Figure 3 is a transverse section through the parts shown in Figure 1.

Figure 4 is a view similar to Figure 1, but 75 enlarged to more fully disclose the construction and illustrate a modification.

Figure 5 is a side view, broken away, of a stringer such as may be used, preferably midway of the side stringers of the stairs, 80 if side stringers are employed, as in wide-stair construction.

Figure 6 is a view showing in perspective, and partly broken away a wall and stairs such as constructed in accordance with this 85 invention, the lowermost stair being bull-nosed if desired.

In my system of construction the stairs are of such a simple nature as to possess especial merit for this reason alone. Where 90 the stairs are made with a form-unit construction, as I shall term it, I employ the spaced longitudinal stringers "A" intermediate the stairs proper which comprise the treads 1 and the risers 2. The stringers "A" 95 are made of ribbed lath of suitable lengths joined together to provide a unit comprising the number of steps required in the particular construction. Any reinforcing lath of metal of the various types being produced 100 today might be employed, however. The spread lath provides an advantageous lath reinforcing shown after a manner at *a*, and the ribs designated *b* forming the reinforcing elements lengthwise of the stringer, in 105 an obvious manner.

The risers and treads are made by bending the lath of which they are comprised

into the desired form and the ribs of the risers and treads, designated 3, constitute the transverse reenforcing elements for the structure, in their relation to the stringers "A."

The risers and treads as a unit are connected with the stringers "A" by wire ties or any similar fastening means, shown best at 4 in Figure 3. The complete reinforced stairs unit is made by applying cement mortar or any suitable cementitious product to the form unit provided by the structure shown in Figure 1. Preferably the stairs section including the risers and treads will be covered by the cement mortar both above and below. Thereafter the cement mortar will be applied to the stringers "A." In this way the mortar applied to the stringers forms shoulders beneath the steps proper.

This, however, would be true whether the mortar is applied to the stringers first, or to the risers and treads, though the first described method will be found best in practice.

Figure 4 shows how reinforcing rods 5 may be readily applied to both the stringers "A" and the risers and treads, to increase the rigidity of the form unit preliminary to the application of cement mortar, when desired.

Middle stringers and, should it be desired, even side stringers may be made by the construction shown in Figure 5, wherein b' designates the reinforcing ribs of metal lath and a' the cut out sections of the upper pairs of lath, cut out to conform with the riser and tread sections of the completed stairs construction.

In Figure 6 I show a concrete wall construction at B', and the stairs "C" are also illustrated, the lowermost one of the stairs being bull-nosed as previously described. Now, if the wall B' be made by the application of cement mortar or concrete to the metal lath, obviously said wall lath may be employed as the stringer section for my stairs "C," the risers and treads reenforcing material designated 2 and 1, respectively, being attached directly to the wall lath section.

The foregoing will indicate how readily adaptable my construction is to the erection of stairs not only for concrete, but also for wooden buildings, and simplicity and cheapness characterize my invention, from the building standpoint, in many different respects. Of great importance, too, is the doing away with the need of temporary

wooden forms for the purposes of construction.

Having thus described my invention, what I claim as new is:

1. A stair construction including a perforate sheet of reinforcement bent to form risers and treads, a stringer reinforcement associated with the first mentioned reinforcement and also formed of perforate material, and a cementitious body applied to opposite sides of the riser and tread and stringer reinforcements and flowing through the perforations thereof to provide a bond between the layers of cementitious material, so that the cementitious material can be applied without a form, the reinforcements being embedded in the cementitious body to provide a monolithic riser and tread and stringer construction.

2. A stair construction including a perforate sheet of reinforcement bent to form risers and treads, a stringer reinforcement associated therewith, supplemental reinforcements extending longitudinally of the risers and treads and stringer reinforcement, and a cementitious body applied to opposite sides of the reinforcements and flowing through the perforations thereof to bond the two layers of cementitious material so that they can be applied without a form, the reinforcements being embedded in the cementitious body, and a monolithic riser and tread and stringer construction being formed.

3. A monolithic stair unit including a sheet of metal lath bent to form risers and treads, a stringer reinforcement connected with the risers and treads, and a cementitious body applied to both sides of the risers and treads and stringer reinforcement so as to completely embed the same and providing a monolithic riser and tread and stringer unit.

4. Reinforced concrete stairs comprising a sheet of reinforcing material bent to form risers and treads, a stringer reinforcement of metal lath associated with the risers and treads and having an edge portion thereof cut out to conform thereto, and a cementitious body applied to opposite sides of the reinforcements and embedding the same to provide a monolithic riser and tread and stringer construction in which the stringer reinforces the stairs on one side thereof without projecting beyond the risers and treads on the other side thereof.

In testimony whereof I affix my signature.
CHARLES W. DONALDSON.
